UNITED STATES PATENT OFFICE.

LE ROY W. STANTON, OF DAVENPORT, IOWA.

TELEPHONE SYSTEM.

1,224,425.

Specification of Letters Patent.

Patented May 1, 1917.

Application filed June 26, 1916. Serial No. 105,891.

To all whom it may concern:

Be it known that I, LE ROY W. STANTON, a citizen of the United States, residing at Davenport, in the county of Scott and State of Iowa, have invented certain new and useful Improvements in Telephone Systems, of which the following is a specification.

The present invention relates to telephone systems and more particularly to the arrangement of circuits and apparatus by which ringing current is applied to the lines for the purpose of signaling a distant station, whether that of a subscriber or that of an operator at an exchange. The invention is herein disclosed in its application to a polystation system wherein subscribers on a single line are selectively signaled. It is also shown as applied to a simple manual system. The invention, however, is capable of more extended use and I therefore do not wish to be limited in this regard. The form chosen for the present disclosure is merely typical. The exact nature of the invention will be more fully understood upon reference to the following detailed description taken in connection with the accompanying drawing, and the scope of the invention will be particularly pointed out in the appended claims.

30 In the drawing, Figure 1 is a diagram of a telephone system embodying the present invention, and Fig. 2 is a detailed view of plug and jack contacts. In these two figures like characters refer to like parts.

35 In the diagram a substation 10 is connected by line limbs 11 and 12 to an exchange where the line is provided with answering jack 13 and multiple jacks, of which one designated 14 is shown. The line is also provided with the usual line relay 15, a cut-off relay 16 and line lamp 17. As shown in the diagram, this line is a calling line. The called line of the diagram, which includes limbs 18 and 19, extends to the central office 40 from substations 20, 21, 22 and 23, the line being a polystation or party line. In this instance the line is provided with jacks 24, 25, 26 and 27, which correspond to the substations on the line and are to be respectively used according to the particular substation which is to be signaled. The line is provided with the usual cut-off relay 28, line relay 29 and line lamp 30. Connection is established between the jacks of the lines

by means of a cord circuit terminating at 55 one end in a plug 31 and at the other end in a plug 32, and having connecting strands 33 and 34. Condensers 35 and 36 are interposed in these strands in the usual way. This cord circuit is provided with supervisory relays 37 and 38, which control supervisory lamp 39, and supervisory relays 40 and 41, which control supervisory lamp 42. An operator's set 43 is adapted to be included in circuit by a listening key 44, and test relay 45 is brought into circuit during the testing operation. In addition, the cord circuit is provided with ringing relays 46, 47, 48 and 49, which are under the control of a relay 50 and operate to bring into circuit generators 51, 52, 53 and 54, severally, according to the particular substation 20, 21, 22 or 23, which is to be signaled.

With this description of the apparatus we may now pass to a description of the operation of the system and this description will bring in other circuits and parts which will be therein sufficiently understood without further preliminary description. If we assume that the party at substation 10 removes 75 his receiver 55 from its hook 56 in the act of initiating a call, it will be seen that he will close a circuit which may be traced to ground from cut off relay contact 57, line limb 12, transmitter 58, switch hook 56, coil 80 59, line limb 11, winding of line relay 15 and battery 60 to ground. This will close the local circuit for lamp 17 through battery 61 and contact 62.

The next act of the operator is to insert 90 plug 31 into answering jack 13. When this is done a circuit is closed from battery 63 through the winding of supervisory relay 38, strand 34, plug and jack sleeve contacts, and the winding of cut-off relay 16 to 95 ground. In addition to this path a path in parallel to that through the winding of relay 16 is provided over cut-off alternate contact 64 through line limb 11, coil 59, switch hook 56, transmitter 58, line limb 12, alternate contact 57, plug and jack tip contacts, the winding of supervisory relay 37, to ground. The closing of this latter path energizes supervisory relay 37 and by opening its normally closed contact 65 prevents 105 the lighting of supervisory lamp 39 upon the closure of contact 66 of relay 38. The closing of the path through cut-off relay 16

cuts off the line relay 15 and extinguishes line lamp 17, and extends the line limbs 11 and 12 to the terminals of the jack.

As soon as the operator has inserted the answering plug into the jack of the calling line, she depresses her listening key 44 and brings her operating set 43 into circuit and receives the order from the calling party. If it be assumed that the calling party desires to converse with a party at substation 20, and that the generator 51 is the generator corresponding to substation 20, that is a generator which will give the requisite frequency to ring the bell at substation 20, then the operator will touch the tip of plug 32 against test contact 67 of jack 27 and if the line is in use there will be a potential above that of normal upon the contact 67, by reason of the connection of the sleeve side of the circuit with battery through the sleeve strand of the other cord circuit which is connected to the line. In case of finding such a potential upon the test contact 67 of the jack 27, there will be a momentary flow of current through the tip of plug 32, normal contacts 68, 69, 70, 71 and 72, and the winding of relay 45 to ground. The closing of this circuit will momentarily energize relay 45 and, by closing its contact 73, momentarily complete a path by which current will flow from battery 74 through the tertiary winding of the induction coil of the operator's set to ground. The result will be a momentary click in the receiver, by which the operator will be advised of the busy condition of the line tested. If such condition be found she will advise the calling party and he will restore his receiver to its hook and the operator will withdraw the plug 31 and all the parts will be left in normal condition awaiting a further call.

In case the line is found to be idle upon the test, the plug 32 is inserted into jack 27 and the tip and sleeve contacts of the jack engage the tip and sleeve strands of the line. These tip and sleeve contacts form a path for the talking current at this point. The third contact 75 of the plug 32 at this time engages ringing contact 76 of jack 27 and thereupon closes a local circuit which will automatically apply the proper ringing current to the line to signal the party at substation 20. It will be noted that when the plug 32 was inserted into jack 27 that the cut-off relay 28 was drawn up and the line limbs 18 and 19 extended to the tip and sleeve contacts of the jack just as in the case of the line limbs 11 and 12 as previously described. The path closed as a result of the engagement of plug and jack contacts 75 and 76 may be traced from contact 76 through conductor 77, battery 78, winding of relay 46, normal contact 79 of relay 50, interrupter 80 and contact 75, to the starting point contact 76. The closing of this cir-

cuit energizes relay 46 and immediately connects the ringing generator 51 into circuit with the called line. The path for ringing current extends from the live pole of generator 51 through alternate contact 71, normal contacts 70, 69, 68, plug and jack tip contacts, alternate contact 81, line limb 18, thence in parallel through the substations 20, 21, 22 and 23 and back to the exchange over line limb 19, thence through alternate contact 82, plug and jack sleeve contacts, normal contacts 83, 84 and 85 of ringing relays 49, 48 and 47, respectively, alternate contact 86 of relay 46, resistance 87 and battery 88 to ground. At the same time current will flow from battery 88 over the sleeve side of the circuit just traced through the winding of cut-off relay to ground, so as to hold the latter energized when the supply from battery 63 is cut off. It may be noted that the path for ringing current through the substations 20, 21, 22 and 23 is the same in each case, but that the only bell which is rung is that which is tuned to the frequency of the particular generator in circuit. Consequently under the assumptions here made the only bell which will be rung when generator 51 is in circuit is that at substation 20. This path for ringing current may be traced in the latter instance from line limb 18 through call bell 89, switch hook 90 and condenser 91 to line limb 19. It may also be noted that when the plug 32 is inserted in jack 27, not only was cut-off relay 28 energized, but the sleeve supervisory relay 41 was also energized by reason of a circuit closed from battery 63 through the winding of relay 41 over the sleeve side of the circuit and through the winding of cut-off relay to ground. The closing of this circuit upon the insertion of plug 32 into jack 27, by energizing relay 41, closes contact 92 and thereby brings supervisory lamp 42 into circuit. This lamp remains lighted until the tip supervisory relay is energized. The interrupter 80 by making and breaking the circuit through the ringing relay 46 alternately connects ringing current to the line and disconnects the same from it. When the interrupter is in open position the generator 51 is disconnected at contact 71 but at this time the tip strand 33 of the cord circuit is completed through to the tip supervisory relay 40. If at the time this path is closed at contact 71, the party at substation 20 removes his receiver from its hook, or as soon thereafter as contact 71 returns to its normal position, current will flow through the substation and back over the line to operate the tip relay 40. The path for this flow of current may be traced from alternate contact 82 of cut-off relay 28, through line limb 19, coil 93, switch hook 90, transmitter 94, line limb 18, alternate contact 81, plug and jack tip contacts, nor-

mal contacts 68, 69, 70 and 71, alternate contact 72, and winding of relay 40 to ground. The closing of this circuit will at once energize relay 40 and the latter by opening contact 95 will extinguish supervisory lamp 42.

At the same time supervisory relay 40 will close a circuit for the winding 96 of relay 50 through closed contact 97 of relay 40 to ground. This circuit will be supplied with current from battery 97^a and as soon as relay 50 is energized a locking circuit will be provided through the locking winding 98 and closed contact 99 of relay 50 and closed contact 100 of relay 41 to ground. The energization of relay 50 will open contact 79 and thereby deenergize ringing relay 46 and prevent the further application of ringing current to the called line.

It will be noted that the interrupter 80 and the contact 79 are in a branch which is common to the parallel branches through the windings of ringing relays 46, 47, 48 and 49, and consequently when this common portion of the circuit is interrupted at contact 79 it will be impossible for any of the ringing relays to be energized.

During conversation the transmitters will be supplied with current from the battery 63 through the supervisory relays and the cord circuit strands out over the line in the usual way. It will be noted that the locking circuit for relay 50 extends through contact 100 of sleeve supervisory relay 41 and consequently it will be impossible to deenergize relay 50 until relay 41 has been deenergized. This will only take place upon the withdrawal of the plug 32 from the associated jack.

If it had been desired to call some other substation then one of the other jacks 24, 25 or 26 would have been used, and in such case local circuits would have been closed through the appropriate ringing relay. The jacks 24, 25 and 26 are associated respectively with the generators 54, 53 and 52, and in the case of jack 24 the local circuit includes conductor 101 and battery 102. In the case of jack 25 the local circuit includes conductor 103 and battery 104. And in the case of jack 26 the local circuit includes conductor 105 and battery 106.

At the conclusion of conversation the restoration of the receivers at the substations causes the display of supervisory lamps 39 and 42 in the usual way and the operator takes down the connection by withdrawing the plugs 31 and 32 from their jacks. When this is done the line circuits assume their normal condition, which is that illustrated. Likewise the relay 41 becomes deenergized and thereby releases relay 50 and the various parts of the cord circuit assume their normal condition, which is also that illustrated.

In operating a system constructed in accordance with the present invention, the

operator does not need to use ringing keys, but there is a jack available to her which corresponds exactly with a desired station. Knowing that she wants a particular station she inserts the plug into the jack corresponding to that station.

What I claim as new and desire to secure by Letters Patent of the United States is:

1. A telephone system comprising a poly-station line; a plurality of connection terminals associated with said line; a link circuit; a connection terminal for connecting said link circuit to said line through any one of said connection terminals; a plurality of sources of ringing current, each being individual to one of the stations on said line; connections for operatively connecting said sources to said link circuit; relays for controlling said connections, each relay corresponding to and being usable only with one of said line connection terminals; and additional connections whereby said relays are operated individually according to the particular line connection terminal used in connecting the link circuit to the line.

2. A telephone system comprising a poly-station line, a plurality of connection terminals associated with said line, a link circuit, a connection terminal for connecting said link circuit to said line through any one of said connection terminals, a plurality of sources of ringing current, connections for individually connecting each of said sources to said link circuit, a relay individual to each of said sources and operative only to control the connections of the particular associated source, and additional connections whereby said relays are individually and selectively operated according to the particular line connection terminal used in connecting the link circuit to the line.

3. A telephone system comprising a poly-station line, a plurality of connection terminals associated with said line, a link circuit, a connection terminal for connecting said link circuit to said line through any one of said connection terminals, connections for providing a local circuit for each of said line connection terminals, a ringing relay in each of said local circuits, sources of ringing current corresponding to said ringing relays, and connections for bringing each of said sources into circuit with the connected line when the corresponding ringing relay is energized.

4. A telephone system including a telephone line of two conductors, substation apparatus, a link circuit having two talking conductors, tip and sleeve terminal contacts for uniting the conductors respectively of said line and link circuit, tip and sleeve relays interposed battery in bridge of said talking conductors, a ringing source, means for connecting said source in circuit with said line conductors when connected to said

link circuit talking conductors, a relay and connections for controlling said means, and connections for controlling said latter relay which are controlled in turn by said tip and 5 sleeve relays.

5. A telephone system comprising a telephone line of two limbs, a link circuit of two strands for connecting with said line, a ringing relay actuated in response to the connection of said line and link circuit, a source of ringing current connected to said line by the actuation of said ringing relay, a control relay for varying the circuit of said ringing 10

relay, and a pair of relays for in turn controlling said control relay, said pair of relays being connected one to one of said link circuit strands and the other to the other and one being controllable over said line and one of said strands and the other being controllable over a local circuit including a portion of the other of said strands and a portion of a limb of the connected line. 15 20

In testimony whereof I have hereunto subscribed my name this 24th day of June, A. D. 1916.

LE ROY W. STANTON.
